UNITED STATES PATENT OFFICE.

ALFRED RITTER JURNITSCHIEK VON WEHRSTEDT, OF VIENNA, AUSTRIA-HUNGARY.

CARTRIDGE-MAGAZINE WITH LOADING-FRAME EJECTOR.

SPECIFICATION forming part of Letters Patent No. 468,394, dated February 9, 1892.

Application filed June 30, 1891. Serial No. 398,096. (No model.)

To all whom it may concern:

Be it known that I, ALFRED RITTER JURNITSCHIEK VON WEHRSTEDT, a subject of the Emperor of Austria-Hungary, residing at Vienna, in the Province of Lower Austria, in the Empire of Austria-Hungary, have invented certain new and useful Improvements in Cartridge-Magazines with Loading-Frame Ejectors for Repeating Fire-Arms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in breech-loading magazine fire-arms, and more especially to the magazine thereof, and has for its object the provision of means for the use of cartridge-holders containing a sufficient number of cartridges to load the magazine, said holder, with its contents, to be introduced into the magazine; also, the provision of feeding devices to feed the cartridges from the holder in the magazine to the receiver, and ejecting mechanism for ejecting the empty holders from said magazine, said ejecting mechanism being timed in its operation to eject the holders when all of the cartridges thereof have been exhausted; also, of means for guiding the bullet end of the cartridges as they are fed from the holder to the receiver; also, of means for unlocking the holder by hand.

To these ends the invention consists in the combination of a breech-loading gun provided with a magazine-chamber immediately below the receiver and in communication therewith, a locking device for locking a cartridge-holder against displacement in the magazine, a feed-lever for feeding the cartridges from the holder to the receiver, an ejector for ejecting the empty holder from the magazine, and guides to guide the magazine when moved by the ejector and to guide the bullet end of the cartridges as they are fed to the receiver.

The invention further consists in structural features and combinations of parts, as will now be fully described, reference being had to the accompanying drawings, in which—

Figure 1 is a longitudinal sectional view of so much of a breech-loading magazine-gun as will be necessary to illustrate my invention, showing the receiver and the breech closed. 55 Fig. 1^a is a view substantially similar to Fig. 1, showing the receiver and breech open and an empty cartridge-holder about to be ejected. Fig. 2 is a like view showing the breech and receiver open. Fig. 3 is a longitudinal vertical sectional view of the magazine. Fig. 4 is a vertical transverse section of the magazine on or about on line α α of Fig. 5. Fig. 5 is a perspective view of said magazine. Fig. 6 is a like view of the locking-lever that serves to lock the cartridge-holder to the magazine. Figs. 7, 8, 9, and 10 are perspective views showing, respectively, the bottom plate of the magazine, the feed-lever for feeding the cartridges from the holder, the ejector-lever for ejecting the empty holder, and the guide-lever that guides the bullet end of the cartridges in their movement to the receiver; and Fig. 11 is a vertical longitudinal sectional view of the magazine and a cartridge-holder of well-known construction in which the cartridges are arranged stepwise. 65 70 75

Similar letters indicate like parts wherever such may occur in the described figures of drawings. 80

B, Figs. 1 and 2, indicate the receiver; B', the breech-bolt of a breech-loading fire-arm of well-known construction, said receiver having formed in its bottom a longitudinal slot for the passage of the cartridges from a magazine arranged below the receiver, and S the stock of the gun, which is suitably chambered below the receiver, said chamber constituting a portion of the magazine. The other portion of the magazine (shown detached in Fig. 90 3) consists of a tapering box or frame A, open at top and bottom, which, for greater convenience, as well as with a view to lessening the number of pieces of the gun, has formed at its rear end the trigger-guard α . At its forward end the frame A is provided with two lugs, in which are formed bearings for the pivot-pins d' and e' of the feed and ejector levers, respectively, and near the trigger-guard end said frame has on each side an upwardly-projecting arm a^2 , said arms serving as guides for the cartridge-holder both when

introduced into or ejected from the magazine. The bottom C of the frame A (shown detached in Fig. 7) has at its forward end a hollow post c^5 for the screw c , by means of which the forward end of the magazine is secured to the receiver, (see Figs. 1 and 2,) the rear end of the magazine being secured to the gun-stock by means of a screw a' passing through a perforation in a lug or tang projecting from the trigger-guard a of the frame. (See Figs. 1 and 2.) The rear strap-swivel I is pivoted on a pin or screw i , fitting a bearing in frame A in front of the trigger-guard a , as shown.

15 The bottom plate C of the frame A has an abutment or rest c^4 in front of post c^5 and near its rear end a horn c^2 , enlarged at the base, as shown at c^3 , to form a seat for the rear end of the cartridge-holder. In rear of 20 the horn c^2 the plate C has a lug or catch c' , that engages an opening a^5 , Fig. 5, in the front wall of the trigger-guard, so that on removing the screw c said bottom plate can be readily removed from the frame and access 25 had to the magazine.

16 The feed-lever E (shown detached in Fig. 9) has the general form of a parallelogram provided with a longitudinal slot e and with a bearing at its forward end for the pivot-pin e' , above referred to, and an upwardly-projecting lip e^2 , for purposes presently explained. At its rear or operative end the lever E is provided with a flattened projection or bearing e^3 , upon which the cartridge-holder 30 rests.

17 The feed-lever D is of substantially the same form as the lever E, its slot d being somewhat shorter than the slot of said lever E. At its rear end said lever has a tongue 35 d^2 , whose upper face is preferably serrated, said tongue having bearing on the cartridges in the holder and being of such width as to readily pass between the side walls of said holder. At its forward end the lever D is chambered out for the reception of a socketed lug d^6 , said lug having a longitudinal slot into which projects a screw d^5 , that limits the movement of the stud under the stress of a coiled spring d^4 on a guide-pin d^3 , secured 40 to the rear vertical wall of the chambered portion of the lever. The outer face of the stud d^6 is recessed to form an abutment or shoulder which has bearing on the lip e^2 of lever E, the lever D being pivoted to frame A, on pin d' above pin e' , as shown, and as arranged the spring-actuated stud d^5 serves to independently revolve both levers on their 45 pivots in one and the same direction.

18 G indicates a locking-lever. (Shown detached in Fig. 6.) Said lever is pivoted on a pin a^3 , that has its bearings in the frame A. (See also Figs. 3, 5, and 11.) The lever G is an angle-lever, whose vertical arm g^4 has a hook g^5 , adapted to engage the cartridge-holder, and, as shown, the lower part of the said vertical arm is chambered to form a housing for a coiled spring g , (shown in dotted

lines in the drawings,) said chambered portion projecting rearwardly of the pivot-bearing g^6 of the lever, the spring, which has bearing on the upper face of the trigger-guard, tending to throw the vertical arm g^4 forward. The horizontal arm g^2 of the lever has at its free end a hooked lug g' , from which depends a finger-piece g^3 , that lies outside of the magazine-wall, (see Fig. 4,) so that the locking-hook g^5 may be disengaged from the cartridge-holder F by hand when it is desired to remove said holder for any cause, the finger-piece extending through a longitudinally-slotted flange or rib a^{12} , formed on frame A. (See Figs. 3 and 5.)

19 H indicates the guide-lever, (shown detached in Fig. 10,) which lever guides the bullet end of the cartridges as they are moved up to the receiver by the feed-lever D, and, as shown, is pivoted to the forward end of the receiver B. (See Figs. 1 and 2.) The free end of the guide-lever lies normally in the forward end of the slots d and e of the feed and ejector levers, and as said feed-lever is tilted upwardly by the spring d^4 the said lever H is also moved upwardly. In its normal position the lever H has bearing against the abutment c^4 on the bottom of the magazine, 50 by which it is held against forward motion. As shown, the lever H has a vertical flange at each side to form a groove that prevents lateral displacement of the bullet end of the cartridges, and thereby insures the proper feeding thereof to the receiver.

20 It will be observed that but a single spring serves to actuate both levers D and E, as well as the guide-lever H, through the medium of the stud d^6 , having bearing on the lip e^2 of lever E, said lever having a fixed relation to lever D until the empty holder is ejected, which takes place when the last cartridge has been fed from the holder F to the receiver B by the feed-lever D, at which time the said lever will strike the hook g' on the free end of the arm g^2 of locking-lever G and tilt the same rearwardly against the stress of its spring g , thereby disengaging the holder F and permitting the ejector-lever E to move upwardly under the pressure of the stud d^6 and carry with it and eject the empty holder F. In Fig. 3 I have shown these parts in their relative positions when the last cartridge in the holder F is about to be carried to the breech by the breech-bolt B'. In Fig. 1 I have shown said parts in their relative positions after the empty holder has been ejected, the levers D and E being at the limit of their upward motion and being held there by the locking-screw d^5 , that prevents further forward motion of the lug d^6 under the stress of the spring d^4 , and hence further pressure upon the lip e^2 of lever E.

21 The cartridge-holder I prefer to use is of the construction fully shown and described in my application for Letters Patent of even date with this, the holder F being substantially a spring-clamp, and the back or bridge

that connects the clamping-jaws being substantially U-shaped in section, not only for the purpose of increasing the elasticity of the jaws, but also for the purpose of providing a bearing for the reception of the horn c^2 on the bottom plate of the magazine to hold the holder F securely in position. The holder at the point of junction of the back or bridge with the jaws has on opposite sides a vertical groove for the flanges of the cartridges which, when inserted in the holder F, lie in contact with each other, as shown in dotted lines in Figs. 2 and 3, whereby they are guided in their movement in the holder.

15 The upper and lower edges of the clamping-jaws f of the holder F, as described in my application aforementioned, are bent inwardly to retain the cartridges.

Although, as stated, I prefer to employ the 20 described holder F, yet I do not desire to limit myself thereto, as other holders of well-known construction may be used, as shown in Fig. 11, the holder F' being of the ordinary form and the cartridges lying therein with 25 their flanges in front of each other or step-wise. In this case the horn c^2 on the bottom plate C of the magazine may be dispensed with, the back of the holder being provided with a lug f' , with which the locking-hook g^5 30 of the lever G engages. The feed-lever D, when an ordinary holder F' is used, is or may be provided at its forward end with a lug e^4 , that bears against the lowermost cartridge, as shown in Fig. 11.

35 Instead of providing the horizontal arm of lever G with a finger-piece, said lever may have a third arm g^4 , terminating in a finger-piece arranged to project through a slot in the front wall of the trigger-guard a —i.e., the rear 40 wall of the frame A, as shown in Fig. 11. In both constructions either the arm g^2 or g^4 performs the function of a detent to release the hook g^5 from the cartridge-holder F or the lug f' of holder F', as the case may be.

45 The operation of the described devices may be briefly described as follows: Supposing the parts to be in the position shown in Fig. 1, the guide H lies nearly horizontal in the slots d and e of feed and ejector levers D and E, 50 respectively, and as the slot d in said lever D is much shorter than the slot e in lever E said guide and the free ends of the levers will practically form a bottom for the receiver, so that on withdrawing the breech-bolt B' the 55 gun may be used as a single loader. If after withdrawal of the breech-bolt it is desired to load the magazine, a cartridge-holder F is shoved into it and into the horn c^2 on bottom plate C, the locking hook or lever G being 60 pressed rearwardly by the holder, which, when fully pushed in, will rest on the seat c^3 and on the ejector-lever, which, with the feed-lever and the guide-lever H, are depressed by the holder F, the jaws f of which lie just in 65 rear of the two guide-arms a^2 , that guide the forward end of the cartridge-shells. When the holder is fully pushed in, the uppermost

cartridge will lie in a position (see Fig. 3) to be engaged by the breech-bolt B' when again moved forward to close the breech, and is thereby carried into the breech. This operation being repeated until all of the cartridges have been removed from the holder, when, as hereinbefore explained, the feed-lever engages the hook g^5 on arm g^2 of lever G and tilts said 75 lever, thereby releasing the holder F, which is immediately ejected, thereby advising the marksman of the fact that the magazine is empty.

Although the loading of the magazine is 80 more conveniently and especially more rapidly effected when the necessary number of cartridges to form a load for the magazine are ready put up in holders, yet it is obvious that the magazine may be supplied with loose cartridges, in which case the horn c^2 and the ejector and locking levers E and G may be dispensed with, a leaf-spring secured to the magazine-bottom being then used to actuate the feed-lever and suitable and well-known 85 retaining devices provided to prevent the load of cartridges from being ejected from the magazine when the breech-bolt is moved back and so that the uppermost cartridge may be seized by said breech-bolt and carried forward into the breech of the gun when the bolt is moved forward. These are modifications 90 that will be apparent to any skilled mechanic, or those conversant with the state of the art.

Having thus described my invention, what 100 I claim as new therein, and desire to secure by Letters Patent, is—

1. In a breech-loading magazine-gun having the magazine arranged immediately below the receiver and in communication therewith, a longitudinally-slotted and spring-actuated feed-lever upon which the cartridges are stacked, in combination with a guide-lever pivoted at the forward end of the receiver and having bearing in the slot of the feed-lever, 105 said guide-lever being provided with a groove for the reception of the bullet end of the cartridges, for the purpose set forth.

2. In a breech-loading magazine-gun in which the magazine is arranged immediately 115 below the receiver, the combination of a cartridge-holder, a lock for locking the holder in the magazine, a feed-lever operating to feed the cartridges vertically from the holder, an ejector-lever having bearing on the holder, 120 and a detent for operating the lock to release the holder, for the purpose set forth.

3. In a breech-loading magazine-gun in which the magazine is arranged immediately 125 below the receiver, the combination of a cartridge-holder, a lock for locking the holder in the magazine, a feed-lever operating to feed the cartridges vertically from the holder, an ejector-lever having bearing on the holder, and a detent operated by the feed-lever for 130 operating the lock to release the holder, for the purpose set forth.

4. In a breech-loading magazine-gun in which the magazine is arranged immediately

below the receiver, the combination of a cartridge-holder, a lock for locking the holder in the magazine, a feed-lever operating to feed the cartridges vertically from the holder, an 5 ejector-lever having bearing on the holder, and a detent operated by the feed-lever for operating the lock to release the holder, said detent being arranged relatively to the feed-lever, so as to be engaged thereby when the 10 last cartridge has been removed from the holder, for the purpose set forth.

5. In a breech-loading magazine-gun in which the magazine is arranged immediately below the receiver, the combination, with a 15 cartridge-holder, a lock to lock the holder in the magazine, a feed-lever operating to feed the cartridges vertically from the holder, an ejector-lever having bearing on the under side of the holder, and a detent for operating the 20 lock to release the holder, of a guide-lever at the front end of the magazine provided with a groove for the reception of the bullet end of the cartridges, said guide-lever moving synchronously with the cartridges, for the 25 purpose set forth.

6. In a breech-loading magazine-gun in which the magazine is arranged immediately below the receiver, the combination, with a cartridge-holder, a lock to lock the holder in 30 the magazine, a feed-lever operating to feed the cartridges vertically from the holder, an ejector-lever having bearing on the under side of the holder, and a detent for operating the lock to release the holder, of a guide-lever at 35 the front end of the magazine, provided with a groove for the reception of the bullet end of the cartridges, said guide-lever receiving motion from the feed-lever, for the purpose set forth.

40 7. In a breech-loading magazine-gun in which the magazine is arranged immediately below the receiver, a magazine frame or box having at its rear end a trigger-guard provided with a perforated tang or lug and a slot 45 a^5 in the front wall of said trigger-guard, in combination with a bottom plate for said magazine, provided at its rear end with a lug or catch adapted to engage the slot a^5 and at its forward end with a hollow post c^5 , substantially as and for the purpose set forth.

8. In a breech-loading magazine-gun in which the magazine is arranged immediately below the receiver, the combination of the horn c^2 , projecting from the bottom of said 55 magazine and having bearing or seat flanges c^3 at the foot thereof, and spring-actuated feed and ejector levers pivoted at the forward end of the magazine at or near the bottom thereof, with a cartridge-holder having at its rear 60 end a vertical groove or socket for the reception of said horn c^2 , and a spring-actuated locking-lever terminating in a hook adapted to engage the upper edge of said rear end of the holder, substantially as and for the 65 purpose set forth.

9. In a breech-loading magazine-gun in which the magazine is arranged immediately

below the receiver, the combination of the horn c^2 , projecting from the bottom of the magazine and having bearing or seat flanges c^3 at the foot thereof, and spring-actuated feed and ejector levers pivoted at or near the bottom of the magazine at its forward end, with a cartridge-holder having at its rear end a vertical groove or socket for the reception of the horn c^2 , a spring-actuated locking-lever adapted to engage the upper edge of the cartridge-holder at its rear end, and a guide-lever pivoted at the front end of the magazine above the feed and ejector levers and having bearing on said feed-lever, said guide-lever being provided with a groove for the reception of the bullet end of the cartridges, substantially as and for the purpose set forth.

10. In a breech-loading magazine-gun in which the magazine is arranged immediately below the receiver, the combination, with the feed, ejector, and guide levers pivoted at the front end of the magazine on superposed independent pivots, said guide-lever having bearing on the feed-lever, of a single spring operating upon the feed and ejector levers to move the same in one and the same direction, for the purpose set forth.

11. In a breech-loading magazine-gun in which the magazine is arranged immediately below the receiver, the combination of the feed-lever having its rear end chambered, a stud or pin having free motion in said chamber, and a spring exerting its power upon said stud with the ejector-lever pivoted in the magazine below the feed-lever and having in rear of its pivot an upwardly-projecting lip on which the end of the spring-actuated stud has bearing, for the purpose set forth.

12. In a breech-loading magazine-gun in which the magazine is arranged immediately below the receiver, the combination of superposed spring-actuated feed and ejector levers pivoted at or near the bottom of the magazine at its forward end and having a determined amplitude of upward motion with a cartridge-holder having bearing on the ejector-lever, the feed-lever having bearing on the lowermost cartridge in the holder, a locking device to lock the holder in the magazine, and a detent for operating the lock to release the holder, for the purpose set forth.

13. In a breech-loading magazine-gun in which the magazine is arranged immediately below the receiver, the combination, with the receiver and longitudinally-slotted and spring-actuated feed and ejector levers pivoted at the forward end of the magazine on superposed pivots and having a determined amplitude of upward motion, of a longitudinally-grooved guide-lever pivoted above the feed and ejector levers and extending into the slots thereof, the length of said guide-lever being such as to nearly fill the slots of said feed and ejector levers when the three levers occupy a given position, for the purpose set forth.

14. In a breech-loading magazine-gun in which the magazine is arranged immediately

below the receiver, the combination, with spring-actuated feed and ejector levers pivoted at the forward end of the magazine at or near the bottom thereof, of a two-armed locking-lever pivoted at the rear end of the magazine, the vertical arm of said lever terminating in a hook and its horizontal arm being provided with a finger-piece projecting outside the magazine, and with an abutment

adapted to be engaged by the feed-lever, for the purpose set forth.

In testimony whereof I affix my signature in presence of two witnesses.
